(57) **CLAIM**

The ornamental design for a fragrance bottle, as shown and described.

DESCRIPTION

FIG. 1 is a front and right side perspective view of our new design for a fragrance bottle;

FIG. 2 is a front elevation view of the fragrance bottle, shown in FIG. 1;

FIG. 3 is a right side elevation view of the fragrance bottle, shown in FIG. 1;

FIG. 4 is a rear elevation view of the fragrance bottle, shown in FIG. 1;

FIG. 5 is a left side elevation view of the fragrance bottle, shown in FIG. 1;

FIG. 6 is a top plan view of the fragrance bottle, shown in FIG. 1;

FIG. 7 is a bottom plan view of the fragrance bottle, shown in FIG. 1; and,

FIG. 8 is an exploded view of the fragrance bottle, shown in FIG. 1.

The broken line showing of a spray pump and portions of the base of the bottle in FIGS. 1, 7 and 8, are included for the purposes of illustration only and form no part of the claimed design.
